UNITED STATES PATENT OFFICE

2,447,942

TURBINE DISTRIBUTOR AND NOZZLE

Roger Jean Imbert, Paris, and Gilbert Mission,
Bagneux, France, assignors to Société Rateau
(Société Anonyme), Paris, France, a company
of France

Application November 1, 1945, Serial No. 626,104
In France December 5, 1944

7 Claims. (Cl. 253—78)

1

The development of thermic machines operating at high temperatures and chiefly of gas turbines presents considerable difficulties by reason of the variations in the distribution of the temperature both in space and in time as a result of variations in the running rate of the machines. As a matter of fact, the different elements of the machines have a different calorific inertia and reach their thermic equilibrium and consequently their normal expansion conditions only a certain time after the load has been stabilised. When the rate of running varies, the elements of the machine are submitted to a succession of expansions and contractions and this is the case in particular for the nozzles and distributors forming the stationary bladings; these latter members should remain fluid-tight with the exception of the passages left open for the flow of gaseiform fluid and moreover they must remain correctly centered with reference to the movable blading of the rotor.

The present invention covers an arrangement for mounting the stationary bladings of gas turbines or generally speaking of the bladings of any turbo-machines operating with fluid at high temperatures; according to the invention, the blades are integral only with a single ring-shaped member and they are mounted on the side opposite to said ring-shaped member in a manner such as will allow radial displacement due to their expansion.

The following description and accompanying corresponding drawings showing by way of example forms of execution of the invention, will allow said invention and the manner of executing same to be easily understood; the features appearing both in the drawings and in the specification form of course part of said invention.

Fig. 1 is a partial axial cross-section showing the usual manner of executing stationary distributors, and Figs. 2 to 5 are corresponding views of different forms of execution improved in accordance with said invention.

Fig. 2 is an axial cross-section of a first type of distributor.

Fig. 3 is a developed cross-section of the stationary blading of said distributor, the cross-section being executed through a coaxial cylinder.

Fig. 4 and 5 are half cross-sections through

2

two axial planes shifted with reference to one another of an intermediary turbine distributor.

Generally heretofore the stationary blades *c* of the turbine distributor were arranged between two ring-shaped members *a* and *b* fitted inside the body *h* of the stator as shown diagrammatically in Fig. 1; the different expansion of these ring-shaped members leads to a compression or to a stretching of the blades.

Fig. 2 shows the application of the invention to a first distributor or injecting nozzles of a turbine operating with gases or with highly superheated steam; the driving fluid enters through the torus *d* and expands between the blades *c* of the nozzle and drives the receiving wheel *e*.

The blades *c* of the expansion nozzle are provided with two heels or end pieces *f* and *g* and are rigidly secured to the outer ring-shaped member *i*, by means of rivets *j* for instance. The outer ring-shaped member *i* is mounted in its turn in a manner such as will allow its free expansion inside the body *h* of the stator by means of a radial system of pins or keys *k* the number of which is at least equal to three.

The fluid-tightness of the mounting of the ring-shaped member *i* inside the stator is provided by the correct machining of the lateral surfaces of said member and of the surfaces of the recess housing it inside the stator *h* and by the pressure of the driving fluid which applies the ring-shaped member against the down-stream side surface of its recess.

The fluid-tightness at the center of the distributor is provided by a free or floating ring *l* bearing, under the action of the pressure of the driving gases passing out of the torus, on one hand against the body of the stator *h*, on the other against the heels *g* of the blades. In order to provide for a proper bearing of the ring-shaped member against the heels *g*, the latter are fitted inside one another by means of the arrangement shown in Fig. 3, in which the bearing surfaces between adjacent blades are illustrated as forming a series of steps.

Figs. 4 and 5 relates more particularly to an intermediary distributor adapted for use either in a gas turbine or in a high pressure steam turbine. Fig. 4 shows more particularly a cross-section through the axis of a blade guiding pin, and Fig. 5 a cross-section through the pin con-

necting the outer ring-shaped member with the body of the turbine. The problem to be solved in this case is more intricate than in that of the nozzles in Figs. 2 and 3, as the guide blades c_1 of the intermediary distributor must necessarily carry the inner ring-shaped member m which carries the packings n providing for fluid tightness along the shaft.

With the form of execution illustrated by way of example the blades are held through their inner heels g_1 which are secured by means of rivets to the inner ring-shaped member m . The outer heels f_1 of the blades which are not mechanically interconnected engage an outer ring shaped member i_1 inside which they are centered by a certain number of pins o the number of which is equal at the utmost to that of the blades. In practice a single pin or key may be provided for a group of two or three consecutive blades.

In order to allow said radially arranged pins to slide during the varying heating and consequent expansion of the different elements connected by them, the outer ring-shaped member i_1 is mounted in its turn in a manner such as will allow its free expansion with reference to the stator h of the machine so that the reactions of the stator are prevented from deforming the pin carrying ring-shaped member. The ring-shaped member i_1 may be guided with reference to the stator by means of radial pins or keys p .

Obviously the above form of execution has been shown solely by way of example and it is possible to modify the forms in various manners chiefly by substituting therefor technical equivalents without widening thereby the scope of the invention as defined by accompanying claims.

What we claim is:

1. In a turbo-machine adapted to operate at high temperatures, the provision of a stationary distributor comprising two coaxial rings, a system of blades arranged between said rings, secured rigidly to only one thereof, and engaging the other ring in a manner allowing the free expansion of the blades with reference thereto and a stator enclosing the two ring-shaped members, the ring-shaped member rigid with the blades being machined along its lateral surface engaging the stator for providing fluidtightness under the action of fluid pressure and allowing the free relative expansion of the ring-shaped member with reference to the stator.

2. In a turbo-machine adapted to operate at high temperatures, the provision of a stationary distributor comprising two coaxial rings, a system of blades arranged between said rings, secured rigidly to only one thereof, and engaging the other ring in a manner allowing the free expansion of the blades with reference thereto, a stator enclosing the two ring-shaped members, the ring-shaped member rigid with the blades being machined along its lateral surface engaging the stator for providing fluid-tightness under the action of fluid pressure and allowing the free relative expansion of the ring-shaped member with reference to the stator and a system of at least three radial pins rigid with the stator and engaging freely the ring-shaped member rigid with the blades for centering said member.

3. In a turbo-machine adapted to operate at high temperatures, the provision of a stationary distributor including a stator, a ring fitted therein, a system of radial blades rigidly secured to said ring and a second floating ring, adapted to bear under the action of gas pressure both

against the periphery of the blades opposed to the periphery engaging the first ring and against the stator.

4. In a turbo-machine adapted to operate at high temperatures, the provision of an intermediary distributor including a central ring-shaped member, a system of radial blades rigidly connected thereto through their inner end, an outer ring-shaped member inside which the outer end of the blades are fitted in a manner such as will allow their free expansion with reference to said outer ring-shaped member, a stator carrying the two ring-shaped members, radial pins rigid with the outer ring-shaped member and freely engaging at least part of the blades through their outer periphery for centering the blade system, said outer ring being fitted inside the stator in a manner such as will allow its free expansion with reference thereto, and radial pins rigid with the stator and freely engaging the outer ring-shaped member for centering same.

5. In a turbo-machine adapted to operate at high temperatures and having a stator and at least one wheel rotatably mounted in said stator, the provision of a stationary distributor cooperating with said wheel and comprising an external and an internal ring coaxially disposed with reference to said wheel, the said external ring being mounted in a circular groove of said stator with a peripheral play allowing the radial expansion of said ring, guiding means radially disposed in said stator for centering said ring in said stator with respect to said wheel and for ensuring the radial expansion of said ring in said play, a system of blades arranged between said internal and said external ring, means for securing rigidly said blades to only one of said rings, and means providing a radial fitting with a peripheral play between said blades and said other ring, said fitting comprising, on said ring and on the blades, planes at right angles with the axis of said wheel and adapted to be applied one against the other by fluid pressure.

6. In a turbo-machine adapted to operate at high temperatures and having a stator and at least one wheel rotatably mounted in said stator, the provision of a stationary distributor cooperating with said wheel and comprising an external and an internal ring coaxially disposed with reference to said wheel, the said external ring being mounted in a circular groove of said stator with a peripheral play allowing the radial expansion of said ring, guiding means for centering said ring on said stator with respect to said wheel and for ensuring the radial expansion of said ring in said play, a system of blades arranged between said internal and said external ring, means for securing rigidly said blades to said internal ring, means providing a radial fitting with a peripheral play between the said blades and the external ring and means for centering said blades in said external ring.

7. In a turbo-machine adapted to operate at high temperatures and having a stator and at least one wheel rotatably mounted in said stator, the provision of a stationary distributor cooperating with said wheel and comprising an external and an internal ring coaxially disposed with reference to said wheel, the said external ring being mounted in a circular groove of said stator with a peripheral play allowing the radial expansion of said ring, guiding means radially disposed on said stator for centering said ring in said stator with respect to said wheel and for ensuring the radial expansion of said ring in said

play, a system of blades arranged between said internal and said external ring, means for securing rigidly said blades to said internal ring, means providing a radial fitting between said blades and said external ring with a peripheral play and pins radially mounted in said ring and said blades for centering said blades in said ring and ensuring the radial expansion of said blades in said ring.
